UNITED STATES PATENT OFFICE.

GEORGE SIEGENTHALER, OF FREMONT, OHIO.

HAME ATTACHMENT.

1,310,636.

Specification of Letters Patent.

Patented July 22, 1919.

Application filed April 23, 1918. Serial No. 230,297.

To all whom it may concern:

Be it known that I, GEORGE SIEGENTHALER, a citizen of the United States, residing at Fremont, in the county of Sandusky and 5 State of Ohio, have invented a new and useful Hame Attachment, of which the following is a specification.

The subject of the present invention is a hame attachment, and the invention has for 10 its object the provision of an interchangeable, adjustable, combined trace-holder and breast-strap holder.

The invention further contemplates the provision of detachable means for securing 15 the breast-strap holder in place.

The invention also aims to generally improve the construction and reduce the cost of manufacture of attachments of this character.

20 With the foregoing and other objects in view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

30 A practical embodiment of the invention is shown in the accompanying drawing, wherein:—

Figure 1 is a view in front elevation of the device showing the same in place upon 35 a hame-bar;

Fig. 2 is a side elevation of the same;

Fig. 3 is a cross section taken on the line 3—3 of Fig. 1.

The present invention is intended as an 40 improvement on my invention for hame attachments for which Letters Patent of the United States were granted to me November 3, 1908, No. 902,845. In that invention the breast-strap ring was held by a cross 45 bar formed integral with the bands and, in constructing the device, it was necessary to insert a split ring after the body of the device had been cast and weld such ring. This multiplied the operations necessary in 50 manufacture and, consequently, increased the cost of the article. In the present invention I have so designed the attachment that the ring may be formed separately and readily inserted in place.

Referring to the drawing by numerals of 55 reference:—

A fragment of the usual hame-bar is indicated by the numeral 1, and the hame-bar is represented as provided with the usual metallic strip 2 which is secured to the bar 60 and extends longitudinally thereof along its outer side edge. The hame-bar for which this attachment is designed has its draft sustaining portion, that is a portion consisting of about five inches of its length adjacent 65 that point at which the trace-holder is usually attached, of practically uniform cross-sectional area.

The interchangeable, adjustable, combined trace and breast-strap holder is indicated 70 generally by the numeral 3, and consists of a pair of looped straps 4 which are, preferably, cast integral with a bridging strip or side 5, from which side projects a loop 6 which forms the trace-holding element of the 75 attachment. For the purpose of strengthening the device, the straps may also be connected by a bridging strip 7.

Lugs 8 are formed on and project forwardly from the straps 4, and these lugs 80 have grooves 9 provided in their opposed faces, the grooves opening at the rear of the lugs and extending forwardly to a point between the rear and front ends of the lugs.

A pin 10 is adapted to be inserted 85 between the lugs 8 with its ends resting in the grooves, and the pin is encircled by the breast-strap ring 11. When the attachment is in place upon the hame-bar the pin 10 and ring 11 are locked in place between the 90 lugs 8.

Any means may be employed for clamping the attachment in adjusted position on the hame-bar but, as shown herein, I employ set screws 12 which are threaded through 95 suitable apertures formed in the attachment and the inner ends of which contact and bind against the metallic strip 2.

From the foregoing it will be evident that the attachment, being interchangeable, may 100 be applied to either hame-bar, and that it may be adjusted longitudinally of the bar to accommodate the draft conditions. It is also evident that the parts of the attachment may be readily formed and assembled, each 105 portion being a complete structure requiring no further operation thereon in the assembling of the attachment.

Having thus described the invention, what is claimed as new and sought by Letters Patent, is:—

A device of the class described comprising a pair of hame-receiving loops and a bridge connecting the loops, the loops having outstanding lugs provided with grooves terminating at their ends within the lugs and opening laterally through the inner surfaces 10 of the loops; a pin having its ends mounted

in the grooves and insertible thereinto from within the loops; and a ring through which the pin passes, the ring extending between the lugs at the rear of the pin.

In testimony that I claim the foregoing 15 as my own, I have hereto affixed my signature in the presence of a witness.

GEORGE SIEGENTHALER.
